UNITED STATES PATENT OFFICE.

JAMES MCBAIN REID, OF PARRY SOUND, ONTARIO, CANADA, ASSIGNOR TO JAMES OLIVER REID AND JAMES MCBAIN REID, TRADING UNDER FIRM NAME J. M. AND J. O. REID, OF PARRY SOUND, CANADA.

BROOM.

Application filed February 4, 1925. Serial No. 6,891.

This invention relates to brooms such as used in dwellings, stores, factories and the like for sweeping floors. In these brooms, the corn is usually permanently secured to the end of the handle, so that when the corn becomes worn, the broom as a whole is discarded. It has also been known to bind the corn together as a separate unit, which corn is removably inserted in a special holder, so that only the corn is discarded when the latter is worn. So far, however, this latter arrangement has not been successful in a commercial way, and the object of my invention is to devise a broom in which the corn is replaceable which will overcome the objections to the arrangements heretofore known, which can be manufactured and sold at but very little over the cost of the ordinary broom and in which the fillers will cost considerably less than a new ordinary broom, in which the broom unit may be quickly and easily removed and replaced, and in which, when in use, the filler, will be firmly held.

A further object is to devise an improved construction of filler in which the individual strands of corn or fibre will be securely held in place so that their falling out is prevented.

I attain my objects by means of the construction hereinafter described and illustrated in the accompanying drawings in which

Fig. 1 is a front view of my improved broom;

Fig. 2 a vertical section through the same;

Fig. 3 a detail showing the method of constructing the filler; and

Fig. 4 a plan view of the completed filler.

Fig. 5 is a side view of the broom.

In the drawings like numerals of reference indicate corresponding parts in the different figures.

1 is the broom corn or fibre which is secured together to form the filler in the following manner. A narrow strip 2 of paper, fabric or other suitable material is provided and to this strip the upper ends of the strands are secured (see Fig. 3) by means of a suitable adhesive material such as glue, cement or the like. Suitable pressure may be applied to ensure firm adhesion between the corn 1 and strip 2. It will be evident, of course, that the strip 2 may be formed of any number of plies. Preferably, after ce-

menting, the strip and corn may be further secured by one or more lines of stitching 3. The strip 2 may be only of sufficient length to form a single filler, or may be long enough to form a number of fillers.

If the latter, enough will be cut off to form a single filler and is wound into a coil as shown particularly in Fig. 4. The coil may be suitably compressed and will be held together by stitching passing through the various folds.

As will be seen particularly from Fig. 2, the filler will be quite thick at its upper end compared to the thickness of the remainder of it, and this extra thickness is of particular advantage when the filler is used in conjunction with my improved holder which I will now describe.

The holder comprises two half sections 4, which will usually be formed as metal stampings, between which the upper end of the filler is received. These sections 4 are hingedly connected at their lower ends. Each section, it will be noted particularly from Fig. 2, is provided with an extension 5 between which the handle is received. To secure together the upper ends of the sections 4 and extensions 5, I provide the sleeve 6. The extensions 5 are provided with aligned grooves 7 on their outer surface and the sleeve 6 with a pair of projections 8. Communicating with the grooves 7 are grooves 9 into which the projections 8 may enter, when the sleeve has been rotated to suitable position, along which groove the projection may slide so that the sleeve may be disengaged from the extensions 5. These grooves 7 are preferably located at the joint between the extensions, being formed partly in each extension.

Forming the grooves 7 in the outside of the extensions 5 will at the same time form ribs on their inner surfaces, and these ribs I utilize to retain the handle 10 in position, the handle being provided with an annular groove into which the ribs extend.

In order to remove a filler, the sleeve 6 is rotated until the projections 8 enter the grooves 9, when the sleeve may be moved upwardly on the handle to disengage it from the extensions 5. The sections 4 may then be opened out. As the filler is usually considerably wider at the bottom than at the top, it is troublesome to pull it upwardly be-

tween the sections, and owing to the increased thickness of the top of the filler hereinbefore referred to it is impossible to move the filler downwardly unless special provision be made. I therefore, as will be seen from Fig. 1, cut back the lower edge of the sections 4 between the hinge connections, so that, when the sections are opened out, an opening sufficiently large for the withdrawal of the head of the filler is provided, while when the sections are closed up, the head of the filler is firmly held.

On the lower end of the handle is provided a long thin projection 11 which extends into a recess 12 formed centrally of the filler. This projection extends, as will be seen from Fig. 2, down below the level of the lower edges of the sections 4 and gives a measure of stiffness to the filler, although the projection is sufficiently flexible not to interfere with the proper use of the broom.

From the above description it will be seen that I have devised a construction which will satisfactorily attain the objects of my invention as set out in the preamble of this specification.

What I claim is:

1. In a broom, the combination of a holder formed of a pair of sections hingedly connected at their lower ends; an extension on the upper end of each section; a handle

adapted to be clamped between said extensions, said handle having an annular groove formed therein, and said extensions being provided with ribs adapted to be received in said annular groove; means for releasably holding said extensions in handle clamping position; and a filler adapted to have its upper portion received between said sections.

2. In a broom, the combination of a holder formed of a pair of sections hingedly connected at their lower ends; an extension on the upper end of each section; a handle adapted to be clamped between said extensions, said handle having an annular groove formed therein, and said extensions being provided with ribs adapted to be received in said annular groove; means for releasably holding said extensions in handle clamping position; and a filler adapted to have its upper portion received between said sections, said filler having its greatest thickness adjacent the head thereof and the lower edges of said sections being cut away between the hinge points to allow the removal of said thicker portions when the sections are opened out.

Signed at Toronto, Canada, this 15th day of January, 1925.

JAMES McBAIN REID.
